UNITED STATES PATENT OFFICE.

WILLIAM D. BUTLER, OF WESTMINSTER, MARYLAND.

VEHICLE-BODY SUPPORT.

SPECIFICATION forming part of Letters Patent No. 716,666, dated December 23, 1902.

Application filed October 4, 1902. Serial No. 125,857. (No model.)

To all whom it may concern:

Be it known that I, WILLIAM D. BUTLER, a citizen of the United States, residing at Westminster, in the county of Carroll and State of Maryland, have invented certain new and useful Improvements in Vehicle-Body Supports, of which the following is a specification.

My invention relates to improvements in vehicle-body supports, and has for its object 10 to provide a support which will permit the body to have a lateral movement independently of the running-gear.

The invention consists in the novel construction and combination of parts to be 15 hereinafter described and claimed, reference being had to the accompanying drawings, in which—

Figure 1 is a perspective view of a vehicle-body and the adjacent supporting mechanism. Fig. 2 is an enlarged view of the two ends of a vehicle-body and illustrates the rock-bar and bearings at each end, the bearings at one end being shown in section, while those at the other end are in side elevation. 25 Fig. 3 is an enlarged detail of one of the rock-bars.

In the drawings, *a* designates the axle; *b*, the fifth-wheel; *c*, the springs, and *d* the bolster supported on top of the springs. A 30 bearing *e* is securely bolted at each end of the bolsters, and each of said bearings is provided with a set-screw *f*. A rock-bar is provided having two parallel ends *g* and *h* and a stretch *i*, which connects said parallel ends, 35 and the ends *g* of said bars are supported in said bolster-bearings *e*, while the ends *h* of said bars project beneath the vehicle-body *j*. These projecting ends *h* of said bars are supported in a body-bearing *k*, which is bolted 40 to the bottom of said body, and each of the body-bearings *k* is provided with set-screws *l*. The ends *g* of the rock-bars are each provided 45 on their upper sides with a circumferential groove *m*, which extends substantially half-way around the said bars. The other ends *h* of said bars are each provided with a circumferential groove *n* on their lower sides, which, like the grooves *m*, also extend about 50 half-way around the said bar. It will thus be seen that the grooves *m* and *n* are in opposite ends of the rock-bars and that the

grooves *m* extend around the upper half of the bars at one end, while the grooves *n* extend around the lower half of said bars at the opposite end. A bearing *o*, secured to the 55 bottom of the vehicle-body *j*, receives the end *h* of the rock-bars and serves as an additional support therefor. It will be clearly seen by reference to Fig. 2 that the set-screws *f* in the bearings *e* take in the grooves *m* on one end 60 of the rock-bar, and that the set-screws *l* of the bearings *k* take in the grooves *n* in the other end of said bars, and that these set-screws serve to hold the ends of said rock-bars in the bearings against any longitudinal 65 displacement, but permit said bars to have a lateral swinging movement. It will also be seen that the body *j* is supported at each corner by a rock-bar.

The advantages of thus supporting a vehicle-body are numerous and only a few need be mentioned. It relieves the body of many jars and jolts caused by the wheels passing over stones and it permits the vehicle to be turned in a small circle, as the body will 75 shift as the front wheels contact with it, thus giving it the same advantage common to vehicles where the front wheels turn under the body.

Having thus described my invention, what 80 I claim as new, and desire to secure by Letters Patent, is—

In a vehicle-body support the combination of the front and rear bolsters; bearings on each end of said bolsters; a vehicle-body between said bolsters and provided on its bottom with a plurality of bearings; a rock-bar supported at its ends by said bolster and body-bearings, said bars at each of their ends having a groove which extends partly around 90 said bar, the groove at one end of each bar being at diametrically opposite sides from the groove at the opposite end and a projection passing through each bearing and entering one of said grooves in the rock-bar for 95 the purpose set forth.

In testimony whereof I affix my signature in the presence of two witnesses.

WILLIAM D. BUTLER.
